CLAIM

The ornamental design for a communication headset, as shown and described.

DESCRIPTION

FIG. 1 is a perspective view of a communication headset showing my new design;

FIG. 2 is a reduced front elevational view thereof;

FIG. 3 is a left side elevational view thereof;

FIG. 4 is a top plan view thereof;

FIG. 5 is a partial rear elevational view thereof, illustrating in phantom lines the attachment of the communication headset to a pair of glasses; and,

FIG. 6 is a left side view of FIG. 2, with the boom shown in a retracted and upwardly hinged position.

The broken lines shown in the Figures, including the wire connecting the earphone and the base, and the clips for attaching the communication headset to a pair of glasses, as well as the position and arrangement of such elements, illustrate the environment only and form no part of the claimed design.
